Assistant Examiner — Jonathan E Fiencke

CLAIM

The ornamental design for a fog machine, as shown and described.

DESCRIPTION

FIG. 1 is a perspective view of a fog machine showing my new design;

FIG. 2 is an alternative perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in the drawing depict environmental subject matter only and form no part of the claimed design.
